TELEPHONE SYSTEM

George Clifford Hartley and William John Reynolds, Aldwych, London, England, assignors to Western Electric Company, Incorporated, New York, N. Y., a corporation of New York

Application February 28, 1935, Serial No. 8,606
In South Africa March 29, 1934

15 Claims. (Cl. 179—17)

This invention relates to automatic or semi-automatic telephone or like exchange systems comprising multi-party subscribers' lines, commonly known as party lines.

5 Areas are known in which the exchanges are of the central battery type, so that the subscribers' telephone sets are normally without local battery supply, but in which on some multi-party lines, for instance, the subscribers' sets are 10 provided with local batteries for talking current purposes.

The local-battery subsets are usually arranged for dialing and signaling over circuits between the subsets and the exchange different in type 15 from the dialing and signaling circuits used between central-battery subsets and the exchange.

The type of circuit used for dialing and signaling between a central-battery subset and the exchange to which it is connected in this country and many other countries is what is known 20 as a "loop" circuit in which a direct current connection is completed between the two wires or legs of a subscriber's line through the subset when the switch-hook is raised, and current is 25 fed round the loop so formed from a battery connection to one leg and an earth connection to the other leg of the line at the exchange.

The type of circuit largely in use for dialing and signaling between a local-battery subset and the exchange to which it is connected is what is known 30 as a "simplex" circuit; the current supply for this circuit is at the exchange, although a local battery is supplied for talking purposes, and current is fed over the two legs of the subscribers' lines in parallel from battery connections to both legs at the exchange to an earth connection to each leg at the subset when the switch-hook is raised. This type of dialing circuit can be used for long lines, and is particularly 35 applicable to multi-party line working since it is not seriously affected by the bell condensers of the parties' subsets.

One object of the invention is to provide means whereby calls from subscribers' lines arranged 45 for different types of signaling can be efficiently and economically dealt with by automatic equipment.

Another object of the invention is to provide improved reverte 50 call arrangements for exchanges comprising party lines, reverte calls being calls between two subscribers on the same party line, whereby no exchange equipment associated in common with a number of subscribers' lines is held in use during such calls.

55 Another object of the invention is to provide

novel means for controlling code ringing in systems using single-motion conversation switches which are set by control switches.

Another object is to improve the pulsing circuit arrangements for controlling the establishing 5 of connections.

One feature of the invention comprises an automatic or semi-automatic central-battery telephone or like exchange system comprising multi-party lines and single-party lines, on some 10 of which the subsets are arranged for signaling between the subsets and the exchange over one type of circuit, and on others of which the subsets are arranged for signaling between the subsets and the exchange over a different type of 15 circuit, and comprising exchange equipment which is associated in common with subscribers' lines requiring both types of signaling circuit, and which includes discriminating means adapted to determine the type of signaling circuit required for a subscriber's line temporarily connected thereto in setting up a connection, current feed equipment, and switching means controlled by the discriminating means for modifying the circuits of the current feed equipment 20 temporarily connected to a subscriber's line. 25

Another feature comprises an automatic or semi-automatic central battery telephone or like exchange system comprising multi-party lines, in which, in a reverte party line call, automatic 30 exchange equipment seizes the busy calling party line, determines that the call is reverte by the simultaneous freeing of both ends of the connection when the calling party hangs up in response to busy tone, and rings the wanted party, 35 and in which, on the reply of the wanted party, the exchange equipment other than that individual to the party line is released.

Another feature of the invention comprises an automatic or semi-automatic central battery 40 telephone or like exchange system comprising multi-party lines, single-motion connector switches, and single-motion digit responsive control switches which are associated with said connector switches and which act both as marker 45 switches for controlling the setting of associated connector switches and as code-ringing control switches.

Another feature is a pulsing circuit in which 50 impulses may be repeated satisfactorily, for the proper control over the establishing of connections, from a pulsing relay that may vary its make and break periods within a wide range of percentages.

The invention will be clearly understood from 55

the following description of one embodiment of the invention which is shown in the accompanying drawings, in which—

Fig. 1 shows the line circuit of a single-party line without local battery and adapted for loop circuit signaling.

Fig. 2 shows the line circuit of a 10-party line without local batteries and adapted for loop circuit signaling.

Fig. 3 shows the line circuit of a 20-party line with local batteries and adapted for simplex circuit signaling.

Figs. 4 and 5 show a link circuit of a rural exchange comprising a 10-level 51-point single-motion finder switch F giving access by means of staggered wipers to a maximum of one hundred lines, and a 10-level 51-point single-motion contactor switch S having two separate sets of wipers and giving access by means of wiper-switching arrangements to a maximum of one hundred junctions and subscribers' lines.

The link circuit also comprises a 25-point single-motion control switch D which uses the first ten points for receiving the first digit dialed, for operating discriminating relays in accordance with the value of the first digit, and for marking the groups of outlets in the bank of switch S. The remaining contacts are used for receiving one or two ringing code digits for calls to party lines. The ringing codes are determined by wipers D. R. 2 and D. R. 1. The bank contacts in level D. R. 2 are each connected to multipled ringing code control contacts on different levels of a ringing code switch in a common ringing and pulse circuit. Lead SRL is multipled to a ringing code switch level giving a standard ringing code for calls to single-party lines, while leads CRL are each multipled to a different level of the ringing code switch giving a different ringing code. The leads CRL control ten codes while connections between corresponding contacts in bank D. R. 1 and ringing code switch act to modify the ten ringing codes via D. R. 2 alone to give a further ten ringing codes. The circuits in the right-hand bottom corner are for signaling to the common ringing and pulse circuit for various purposes. The chain dotted figures GFE and DFE show the current feed equipment to the calling and called lines respectively. The circuits of these equipments are normally arranged for loop signaling but either can be modified to provide a simplex signaling circuit by relay SI or relay DX respectively. Relay SI is operated via wiper F. D. 5 if a calling line requires simplex signaling while DX is operated via wiper S. D₁ or S. D₂ if a called line requires simplex signaling.

Detailed description will now be given of the embodiment shown in Figs. 2, 3, 4 and 5 of the drawings.

When the subscriber lifts his receiver the line relay L operates in one of the following circuits:—

For CB circuits from battery, relay L, Figs. 1 and 2 K₁, subscriber's loop, K₂, earth.

For simplex circuits from battery, relay L, Fig. 3 K₁ to earth at the subscriber's station.

L operates SA Fig. 4 (battery, SA, K₃, L₁, earth) and connects battery via low resistance right-hand winding of K, Figs. 1, 2 and 3, K₄ to the H banks of the F switches Fig. 4 to mark the calling line. SA connects earth to a free link via the start chain, which distributes calls. ST in the link Figs. 4 and 5 operates (battery magnet DM, and interrupter springs, switch D,

H wiper and home contact, switch S, wiper D₂ and home contact, relay ST, BB₂, start chain, SA₁, earth). ST operates relay B and drives the F switch in search of the calling line (battery, magnet FM, and interrupter springs, ST₁, LH₁, P₁, H₆, JM₃, ST₂, earth). B is pre-energized by ST in order to reduce the seizing time of the circuit. When F reaches the calling line, P operates (low resistance battery in line circuit, F. H. wiper, ST₃, relay P, earth), opens the F driving circuit at P₁ and locks (battery, resistance YL, ST₅, relay P, P₁, H₆, JM₃, ST₂, earth). At P₂ earth is connected via ST₃ to the line circuit H lead which makes the line busy on the S switch multiple. Relay K Figs. 1, 2 or 3 in the line circuit operates in series with a holding winding of L to the same earth and at K₁ and K₂ disconnects the line circuit feed from the subscriber's line. L now holds in series with K. P also operates LH (battery, YM, relay LH, ST₄, P₁, H₆, JM₃, ST₂, earth). LH locks via B₁ to LH₅, and at LH₂, LH₃ connects the subscriber's line through to the AS relay via F₊ and F₋ wipers and banks. The link now discriminates as to whether the call is from a simplex line, an ordinary CB line, or a long single-party CB line. This is performed by means of the D bank of the switch F. Relay SI is multipled to contacts in bank D of F corresponding to simplex lines, LL is multipled to contacts corresponding to long C. B. lines, and R to contacts corresponding to coin box lines.

If the line is a simplex one relay SI operates via this bank and connects center point battery to the subscriber's line. This circuit may be traced from battery, lower windings of relays AS and TC, TC₂ or resistance YH, SI₁, upper windings of AS and TC, TC₁ or resistance YV, SI₂, via SD windings in parallel to the positive line via the upper winding of SD, and via the lower winding of SD and SI₃ to the negative line. AS operates to the center point earth in the subscriber's set. In neither case is there any current flow to the relay A as this is operated by rectifier MRA.

In the case of a CB subscriber SI does not operate and the subscriber's talking feed is supplied from battery via lower windings of AS; TC, at SI₃, to the negative line and from earth via SI₂, upper windings of TC and AS and SI₁ to the positive line.

In the case of long single-party lines, relay or impedance LL is energized via the D bank and modifies the magnetic field of the impulsing relay AS. LL is mounted adjacent to AS and by setting up an external magnetic field assists the impulsing on these long lines.

Relay TC is marginal and operates on lines having less than 150-ohms resistance. At TC₁ and TC₂ it introduces additional resistance into the feed in order to reduce the transmitter current on these short lines.

Relay AS operates relay A via AA₁, AS₁ and A operates BB and AA in obvious circuits. Relay BB locks via LH₇ to BB₃ and the same earth from BB₃ is extended via A₄ to hold B when ST subsequently releases.

Relay K releases relay SA unless another line is calling, and SA releases ST. ST is slow to release in order to allow time for the operation of LH, AS, A and BB. If SA is held by another calling line, BB releases ST at BB₂. Contacts LH₅ maintain earth on the H lead when ST₃ opens. ST releases P at ST₅ and ST₄ and opens the original driving circuit for F. BB₁ now sup-

plies the common earth for the circuit in place of ST2, and this earth is extended via JM3, HH4, BB6 and switch D.C wiper and home contact to the dial tone start lead DTS. Dial tone is connected via lead DT, switch D, R2 wiper and S.T1 wiper, J4, CC3, H5, condenser QG, XG4, QD to the negative line. When AA operates A is held via resistance YU, A1 and AS1. The link is now held by the calling subscriber and is ready to receive impulsion.

Failure to dial

While the circuit is waiting for impulsion to commence battery is connected via resistance YN, 15 H4, LH6, relay ZA, ZA3, to lead TA to start the time pulse-machine and thus connect a tuned A pulse to the lead TA. This lead is connected to a high resistance time pulse start relay (not shown) and ZA does not operate. When the A 20 pulse condition is given the high resistance winding is replaced by a low resistance winding and ZA operates. ZA locks via the hold lead HL, prepares a circuit for forced release of the link circuit and holes the time pulse start relay via 25 the hold lead HL. After a predetermined period of about half a minute earth is connected to the Z pulse lead ZL, and if ZA is still up, that is if the subscriber has failed to dial, LH is short-circuited and releases. LH releases AS at LH2 and 30 LH3, and ZA at LH6. LH4 removes earth from the H lead, which releases relay L. During the release of L, K remains held via its left-hand winding and its high resistance middle winding in series with resistance YA, K3 and L1. When 35 L has released, K is connected to the subscriber's line and remains held to the calling condition. In the CB circuits, Figs. 1 and 2, K is held via its left-hand and middle windings, L2, K1, subscriber's loop, L4 to earth; in the L.B. circuit, 40 Fig. 3, K is held via its left-hand and middle windings, L2, K1, to earth at the subscriber's station. The line circuit remains locked in this condition until the P.G. is cleared. On release of AS in the link circuit A releases followed by 45 AA and B; B releases BB and link circuit returns to normal.

First digit received

The subscriber dials the first digit, relay AS 50 responds to the openings in the subscriber's subset circuit and steps switch D by means of the impulse correcting relays A and AA as follows.

On release of AS, A releases followed by AA which releases slowly due to the rectifier RR. 55 On release of AA, A can now reoperate, if AS has reoperated, via AA1, AS1. In the case of a short break if AS reoperates very quickly A is prevented by AA from reoperating too soon. At the end of the first impulse, when AA is back A 60 operates and locks to earth via AA2 A2. AS has a locking circuit for its lower winding via rectifier MRA, A1, resistance YU, AA1, AS1 to earth. This circuit ensures the reception of a very short make, sufficient only to operate the light contact 65 AS1. AA reoperates and if AS is still up A holds via A1. At the beginning of the second impulse AS releases releasing A and the cycle is repeated. On the first release of A switch D is energized and relay C operates (battery, switch magnet DM, EI, G2, HH3, relay C, A5, BB4). C 70 operates CC via C1 to the common ground BB1. When A reoperates D steps to the first contact disconnecting leads DTS, DT. The interaction of relays A and AA is such that the impulses given to the D switch and B relay via A are ap-

proximately 50 per cent make and break for a wide range of make and break percentage on the AS1 contact. Satisfactory impulsion is obtained although the line conditions may give make or break percentage on AS of over 90 per cent.

A opens the circuit B at A4, but B is slow to release and holds during impulsion. C also holds during impulsion. On the first step of D, M operates (battery, resistance YS, relay M, V2, S, C 10 wiper and bank, D.C wiper and bank, BB6, HH4, JM3, to the common ground). D continues stepping until the end of the digit. On the third step (if three or over is dialed) M releases and earth is connected via D.R1 bank and wiper, BB7, S.N bank, home contact and wiper, E1, S interrupters to the magnet SM). S steps off normal and drives until it reaches the beginning of the group indicated by the position of D. The driving circuit for S is via the off normal arc N, G4, V1, M1, LH1, P1, H6 to the common ground. M then operates via wipers S.C and D.C and the marking connections and at M1 opens the driving circuit for S. Contacts 1, 2 of wiper D.C are connected to contact 1 of wiper S.C, contacts 3, 4 of wiper D.C are connected to contact 11 of wiper S. C and so on. If switch S reaches its contacts 11 while D is still on its contacts 3 or 4, M operates and stops S; if D then steps to contacts 5, S steps on to contacts 21 unless or until D steps to contacts 1, and so on. In this way the position of S is controlled by relay M dependent on the position reached by D. At the end of the digit contacts A5 remain open and C releases followed by CC. If S has now reached the contact marked by D, or when it does so, M operates and earth is connected from the common ground via H6, P1, LH1, M1, CC2, E2, to the D wiper of switch D. This operates discriminating relays which control the subsequent operation of the call.

If the digit dialed is even (2, 4, 6 or 8) J (local call) operates and locks to BB3. J operates E (battery, relay E, OG5, J3, HH4 to common ground). If an odd digit is dialed E operates directly. If O is dialed indicating an outgoing call OG operates and extends its operating earth via OG2 to J which also operates and locks.

Local call

On a local call, as described in the last paragraph, relay E is up and J is also up if the first digit is even. D is resting on the outlet corresponding to the first digit and switch S is held under control of M on the outlet preceding the tens group required. Relays AS, A, AA, B, BB, LH, M, and E are up and relays SI, LL, ZA and J may also be up. E locks via E5 to the common ground and drives switch D to the eleventh contact (battery, magnet DM, interrupter springs, contacts 1-10 of the D. H. bank, E6).

When D drives M releases but E1 prevents the driving of S. If J is up, it switches over to the even banks of the S switch.

The circuit is now ready to receive the units digit of the subscriber's number. The impulsion circuit operates as described previously but since contacts E1 are operated, the impulsion circuit comprises magnet SM instead of DM and switch S is stepped. The units digit might equally well be received by switch D, the switch S being set to the wanted line under control of D. C and CC operate as before and S reaches the required subscriber's line. At the end of the digit C releases and at C1 removes earth from the CC winding.

CC now holds via CC₁, E₂, D.D wiper in series with relay G, F₁, DD₄ to the common ground, and G can now operate due to the removal of the short circuiting earth at C₁. G locks on its 5 second winding via G₁ and subsequent operation depends upon whether the called line is a P.B.X. line, party line, or regular line. The discrimination is determined by bank S.D₁ or S.D₂ according to the condition of contacts J₅. Contacts 10 in these banks corresponding to P.B.X. first lines are connected to relay V, contacts corresponding to C.B.10-party lines to relay X, and contacts corresponding to L.B simplex 20-party lines to relay DX.

15 *Call to a single-party regular line*

G operates FF (battery, relay FF, F₂, G₃ to common ground) and JM. JM releases E at JM₃. On the release of E, P is connected to the test 20 lead of the called line (earth, P relay, JM₂, E₃, CC₃, J₄ to test bank T₁ or T₂ of S). CC is released by E₂ but due to the shunt YT, releases slowly and during its release P tests whether the line is free. On release of E, XG operates 25 (battery, XG winding, E₄, G₆, rectifier MRB, LH₅, earth) to indicate end of selection. The impulsing and drive circuits are open at G₄ and G₂ when E releases. If the line is free, P operates in series with the low resistance right-hand 30 winding of K in the line circuit. P short circuits its 100-ohm winding at P₂ to busy the line, as described previously, and locks on its 20-ohm winding (battery, resistance YK, H₂, G₇, relay P, P₁, H₆ to common ground). L and K operate in 35 series in the line circuit on their right and left-hand windings respectively and relay H operates in series with P in the link circuit. H locks at H₁ and operates HH at H₂. H₆ releases P and H₃ maintains earth on the test lead of the 40 line circuit. HH switches the transmission circuit through to the subscriber's line at HH₅ and HH₆. The ring start circuit is energized by battery via H₄, XG₂, relay RS and lead RSL. ZA is released if up. When the ring start pulse arrives, low resistance earth is connected to the 45 ring start lead RSL and RS operates. RS locks (battery, RS left-hand winding, RS₂, G₁, F₁, DD₄ to common ground) and connects a winding of 50 relay R via RS₆ and DR₂ bank to the standard ringing lead SRL on the ringing code switch (not shown) in the ringing circuit. As the ringing code switch steps earth at the standard ringing period is connected to DR₂ bank and R responds. 55 R connects ringing via lead RL, R₁, RS₁, HH₅ and J₁ to the subscriber's line returning via J₂, HH₆, RS₄, DX₅ to earth on lead ERL. At each release of R relay F is connected at R₁ to the subscriber's line and tests whether he has replied. Ringing tone is connected via lead RTL, condenser QH, HH₁, V₅, XG₄, condenser QD to the calling party.

When the called subscriber replies F operates and releases FF at F₂. On release of FF, G and 60 RS release since FF₁ and F₁ are both open and RS connects DS and IS to the subscriber's line. G releases XG at G₆ and XG disconnects ringing tone and the ringing circuit. On release of G, HH keeps the impulsing circuit open at HH₃. IS and DS operate in series with the subscriber's 65 loop and IS operates DD (battery, DD winding, R₂, HH₂, IS₁). DD connects battery via 300-ohm resistance YF and via JM₁, DD₁, OG₈ to the calling subscriber's meter lead and operates 70 the subscriber's meter. The meter is marginal

and does not operate in series with the 2000-ohm resistance YG. JM has been holding via OG₆, DD₃ and JM₃ and via contacts G₃. Contacts DD₃ are now opened. On release of G, JM releases slowly and disconnects battery via resistance YF from the meter lead again. Relays AS, A, AA, B, BB, H, HH, IS, DS are now up and conversation proceeds. DD reverses the positive and negative lines at DD₁, DD₂, DD₅, DD₆ to give supervision to a calling operator on incoming 10 manual calls, or for coin box signaling purposes.

When the calling party clears, AS releases followed by A, AA, and B in turn. B releases LH; LH releases BB. Contacts LH₄ disconnect earth from the finder H lead and release the calling line circuit relays. BB releases H, HH and J if up. HH releases IS, DS and DD and H releases the called party's line circuit. If the called loop is still complete, K in the line circuit remains held to it in the P.G. condition.

Switches S and D drive home in the following circuits—battery, magnet SM and interrupter springs, E₁, S wiper and bank N, BB₁; and battery, magnet DM and interrupter springs, D wiper H bank, E₆ to BB₃ at contacts 11 and 12, 25 DX₃, X₅ and OG₁ at contact 13, and BB₄ at contacts 14 to 24. When these switches reach the home position, the start circuit via ST is complete again.

If the called party clears first, DS and IS release and IS releases DD. DS₂ connects battery via H₆ and XG₂ to the ZA relay. The time pulse start lead is energized and when the A pulse arrives ZA operates, locks and prepares a forced release circuit for LH. If the calling party continues to hold the link circuit, LH is released when the Z pulse arrives and releases the link circuit. AS, A, AA, B and BB release and BB releases the other held relays. The calling line circuit locks to the P.G. condition, as described previously, and called line circuit is released at H₃.

If the called line is busy, P fails to operate before the release of CC. At CC₃ the testing circuit is disconnected. XG operates, as described previously, and busy tone is connected to the 45 calling line from lead BTL via HH₁, V₅, XG₄, condenser QD and the negative lead.

Call to P.B.X. group

The S switch is positioned on the first line of 50 the group and relays AS, A, AA, B, BB, LH, E, CC and G are up; SI or J may also be up. The first line of the P.B.X. group is distinguished by being connected to the V relay on the D₁ or D₂ bank of S. When G operates, V operates via S.D₁ bank, J₅, HH₃, G₃ to the common ground. V locks via M₂ and V₃. FF and JM operate, as described previously, and E releases. Until the operation of JM, M operates for a moment without effect via V₂, E₅, JM₃ to common earth. With V up CC holds via V₁, M₁, LH₁, P₁, H₆ to the common ground, and extends this earth via CC₁ and V₄ to the magnet SM. S drives over the P.B.X. group and P tests each line via the testing circuit described previously. During this hunting for a 65 free line in the group, V₅ keeps busy tone disconnected from the line. When a free line is reached (this may, of course, be the first line) P operates and opens the driving circuit for S at P₁; P₁ also releases CC. H and HH operate, as described 70 previously, and HH₃ releases V. The call now proceeds normally.

If an intermediate or last line of the P.B.X. is dialed, the call proceeds as for a regular line.

If all the P.B.X. lines are busy M operates when 75

S reaches the last line of the group (battery, resistance YS, relay M, V2, P.B.X. last line on S.D1 or S.D2 bank, J5, HH8, G3 to common ground). M releases V at M2 and opens the driving circuit for S at M1. V releases M at V2 but V1 is now back and CC continues its release. On the release of V, busy tone is connected via XG4 to the calling line. If the last line is free P operates as well as M, and the operation of M is immaterial.

Call to C. B. 10-party line

Relays AS, A, AA, B, BB, LH, E, CC and G are up; SI and J may also be up. Switch S is positioned on the called line and if it is a 10-party line X operates via the D1 or D2 bank (battery, relay X, S.D2 bank and wiper, J5, HH8, G3 to common ground). X locks via X1 and holds E from common earth via X4, RC1, XG6, E5 and OG5 on the operation of JM. JM and FF operate as described previously. X now drives D from contact 11 to contact 13 (battery, magnet DM and interrupter springs, D. H wiper bank, X5, OG7, to earth). With E up CC remains held 25 in series first with relay G on contact 11 and then with relay X on contact 12, but releases when D steps on to contact 13. The circuit is now ready to receive the third digit. This digit indicates the party required and is received by the 30 D switch (battery, magnet DM, X2, E3, G2, HH3, relay C, A5, BB4, earth). The position of D now indicates the ringing code required. C and CC operate during the digit and at the end of the digit C releases and at C1 removes a short circuit 35 from the XG relay. XG operates (battery, CC relay, CC1, E2, D.D wiper and bank, OG1, XG relay to common ground). XG locks via XG1, G6, rectifier MRB, to LH5 and releases E at XG6. As before, XG indicates the end of selection in the 40 link. E opens the impulsive circuit at E3 and closes the line testing circuit at E8. CC releases as before and if the line is free, P and H operate during its release. HH operates and RS operates to the ringing start pulse as described previously. 45 RS connects R to the ringing code required via the D.R2 bank. R responds to the ringing code ground and connects ringing to the line as described previously for the standard code. The operation of RS by a ringing start pulse insures 50 that a clipped code is not connected to the called line.

If the subscriber's line is busy, P and H do not operate and on the release of CC, RC operates (battery, relay RC, X3, XG3, H5, CC3, J4, S bank 55 T1 or T2, to earth in the link which is busying the called line). RC is operated in order to prepare for revertive calling conditions, described later. XG4 connects busy tone to the calling line.

Call to local battery 20-party line

Relays AS, A, AA, B, BB, LH, E, CC and G are up; SI and J may also be up. Switch S is resting on the called line and if it is a 20-party line DX operates via the S.D1 or S.D2 bank. DX locks 60 via DX3 and holds E from common earth via DX1, RC1, XG6, E5 and OG5; FF and JM operate as before and the circuit is ready to receive the third digit. In this case, switch D does not drive since X is not up. The third digit is accepted by 65 magnet DM via DX6, E3 and G2. The digit dialed will be either 1 or 2; if it is 1, X operates in series with CC via contact 12 of bank D.D, when C releases at the end of a digit and removes the short circuit from the 200-ohm winding of 70 X. X locks via X1 and G3, and steps D to contact 75 X.

XG4 to contact 13 by connecting earth via OG7, X5 to contact 12 of the D.H bank. If the digit dialed is 2, D is stepped to contact 13 and X does not operate. C1 releases CC. The circuit now waits for the fourth digit.

The fourth digit is accepted by D as before so that it is positioned on the required ringing code. When C releases at the end of the digit, XG operates in series with CC as described previously. XG releases E at XG6 and the line is tested. If the line is free, PH and HH operate and switch through; RS operates when the ring start pulse is received and code ringing is connected to the line by the operation of R to the ringing code pulses. If the third digit is 1, X is up and R 15 responds to one of the ten basic ringing codes received via the D.R2 bank. The other ten ringing codes which are required if the third digit is 2 are obtained by adding a pulse to each of the ten basic codes. This pulse is received by R 20 via the D.R1 bank on its lower winding, X being back in this condition. Two ringing code pulse leads are shown since in one case slightly different timing is required from that of the other codes. There is no reason why these additional 25 code pulses should be limited to two.

Since DX is up, relay F is connected to both lines in parallel when R is deenergized so that F trips to the center point earth via both lines. With R up, however, ringing still goes out on 30 the positive line returning via the negative line. When the subscriber replies, DS and IS both operate to the center point earth at the subscriber's station, since DS is now connected to battery via DX2.

If the line is busy, E and CC release and RC operates as described for the 10-party line case.

Instead of having two ringing code digits, it would be possible to have one such digit only, if each ten subscribers on the party line were given 40 a separate directory number. This, however, would complicate the revertive call arrangements. Alternatively, two code digits could be used for both types of party line, the first digit not having any function with regard to ringing 45 code selection.

Release from a "busy" or "no reply" call

If the called subscriber does not reply, the link releases when the calling subscriber clears. 50 AS, A, AA and B release in turn, B releases HH which releases BB and BB releases the other party relays. D and S drive home and the link circuit becomes normal.

In the case of a busy call, when the subscriber clears release is similar. If, however, the subscriber continues to hold the link circuit ZA is operated by battery via LH6 when the A pulse arrives, and when the Z pulse arrives, LH is short-circuited and the link releases. The call 55 line circuit locks up in the P. G. condition.

Revertive calls

Relays AS, A, AA, B, BB, LH, G, XG, JM, FF and RC are up; SI, J, X and DX may also be up. 65 If a revertive call is being made, the S and F switches are both positioned on the same line circuit and busy tone is being returned to the calling party. RC is held via X3 or DX4, XG3, H5, CC3, J4, S wiper T1 or T2, F wiper H to LH4. 70 If, however, the call is to a different busy party line, F and S will not be positioned on the same line circuit.

The calling party replaces his receiver, AS releases followed by A, AA, B and LH, but since 75

RC is up, BB remains held via RC3, BB3. LH releases ZA at LH6 and SI if up at LH5. At LH4 earth is removed from the F.H lead and RC starts releasing. However, RH is applied to the line 5 test lead by the release of LH8 before RC has time to release, the circuit extending over the closed contacts RC4. If the call is a revertive one, RH operates in series with the line circuit relays L and K, which hold. RH locks via RH2 and holds 10 RC via G5, RH1 and RC2. The holding earth of RC is extended via X3 or DX4 to the line circuit relays. LH releases XG, at LH5, and RH operates H via RH3, BB1. H now holds the line circuit at H3. HH also operates via H2, RH3, BB1 and 15 reoperates XG via E4, G6, HH7, RC1 and DX1 or X4.

RS operates to the ringing start pulse and code ringing is sent out on the line. When the called 20 party replies ringing is tripped in the normal way; F operates and releases FF which releases G and RS; G releases XG and RC. DS and IS operate to the answering conditions and IS operates DD. DD releases JM and X if up. On release of G earth is connected to the lead F.M 25 during release of RC.

In the case of 10-party C.B. lines this ground 30 operates the transmission feed relay R in the line circuit which connects itself to the subscriber's loop, supplies transmission feed and remains held by the loop until the end of the 35 call. The earth has no effect on a local-battery line as the meter is connected to earth. On release of RC, BB releases followed by the remaining link circuit relays. S and D drive home and the link circuit becomes normal.

The line circuit locks to the calling condition 40 until the end of the call. When both subscribers clear the line circuit releases.

If a subscriber makes a revertive call and fails 45 to clear after getting busy tone, the link circuit is forcibly released by the Z pulse which causes the release of LH so that the circuit goes into the revertive calling condition. Ringing is immediately tripped since the calling subscriber is on 50 the line. The line circuit is then left in a revertive calling condition dependent on the calling loop alone.

In the case of a call to a busy party line, when 55 the calling party clears AS, A, AA, B and LH release, and RC commences to release. Since the subscriber still remains busy, RH does not operate and at the release of RC, BB releases followed by the remaining relays. SD drives home and the link circuit becomes normal.

55 What is claimed is:

1. In a telephone system, an exchange, two 60 types of subscribers' lines terminating in said exchange and arranged for different types of signaling, current feed equipment at said exchange, and means responsive to a subscriber of either 65 type of line calling the exchange for establishing a connection from said current feed equipment to the calling subscriber's line to permit the particular type of signaling required for the calling line 70 to become effective at the exchange.

2. In a telephone system, an exchange, subscribers' lines adapted for simplex dialing terminating at said exchange, subscribers' lines adapted for loop dialing terminating in said exchange, 75 current feed equipment for dialing at the exchange, means for connecting a calling line to said current feed equipment for reception of dialing signals, discriminating means for determining the type of line calling and switching means controlled by said discriminating means for modi-

fying the current feed equipment to permit the type of dialing required by the calling line.

3. In a telephone system, an exchange, subscribers' lines adapted for simplex dialing and signaling, subscribers' lines adapted for loop dialing and signaling, exchange equipment common to said lines for establishing connections between calling lines and called lines including discriminating means for determining the type of line calling and the type of line called, means controlled by said discriminating means for varying the exchange equipment to respond to the type of dialing transmitted by the calling line and to signal with the type of signals required by the called line.

4. In a telephone system, an exchange, subscribers' lines adapted for simplex signaling current feed, subscribers' lines adapted for loop signaling current feed, connector circuits each including current feed equipment and discriminating means for determining the type of current feed required for connection to and signaling over a called line, and switching means controlled by said discriminating means for modifying said equipment in accordance with the type of signaling required by the called line.

5. In a telephone system, multi-party lines, exchange equipment operative in case of a revertive call for establishing a connection from the calling line terminals to the exchange equipment and for 30 finding the called line terminal of the same line, means responsive in said exchange equipment when the calling party replaces his receiver on the switch-hook in response to the calling line testing busy for freeing the calling line terminals 35 from the connection and ringing the called party over the called line terminals, and means responsive to the called party answering for releasing the connection through the exchange equipment.

6. In a telephone system, party lines, connector 40 switches, a digit responsive control switch associated with each connector switch, and means operative by said control switch in making calls from one line to another or from one party to another on the same line for marking lines to which 45 connections are to be made over the associated connector switch and for selecting the ringing code to call the desired party on the wanted line and controlling the ringing of the desired party.

7. In a telephone system, an exchange, short 50 and long subscribers' lines, adapted for simplex current feed, short and long subscribers' lines adapted for loop signaling current feed, connector circuits each including a current feed relay and a marginal relay, two impedances and a source 55 of current with battery normally connected to one leg of a subscriber's line via one winding of the current feed relay, one winding of the marginal relay and one impedance, and ground normally connected to the other leg of the subscriber's line via another winding of the current feed relay, another winding of the marginal relay and another impedance and with the impedances normally short-circuited through contacts of the marginal relay, said marginal relay being operative 60 only when the connector circuit is connected to short lines to include the impedances, a discriminating relay operative when the connector circuit is connected to a calling or called line adapted for simplex current feed for connecting 65 the battery in both windings of both relays and the impedances in series connection to both legs of the connected line in simplex.

8. In a telephone system, an exchange, short 70 and long subscribers' lines, connector circuits 75

- each including a current feed relay and a marginal relay, two impedances and a source of current with battery normally connected to one leg of a subscriber's line via one winding of the current feed relay, one winding of the marginal relay and one impedance, and ground normally connected to the other leg of the subscriber's line via another winding of the current feed relay, another winding of the marginal relay and another impedance and with the impedances normally short-circuited through contacts of the marginal relay, said marginal relay being operative only when the connector circuit is connected to short lines to include the impedances. 5
9. In a telephone system, an exchange, short and long subscribers' lines, connector circuits each including a current feed relay and a marginal relay, two impedances and a source of current with battery normally connected to one leg 10 of a subscriber's line via one winding of the current feed relay, one winding of the marginal relay and one impedance, and ground normally connected to the other leg of a subscriber's line via another winding of the current feed relay, another winding of the marginal relay and another impedance and with the impedances normally short-circuited through contacts of the marginal relay, said marginal relay being operative only when the connector circuit is connected to short lines to include the impedances, 15 another relay having an inductive winding in each connector circuit, means for operating said relay when a long line is connected to a connector circuit, said other relay being so placed 20 in relation to the current feed relay in the same connector circuit that its magnetic field aids the magnetic field in the current feed relay winding. 25
10. In a telephone system, subscribers' lines adapted for simplex signaling, subscribers' lines 30 adapted for loop signaling, a connector switch, a circuit therefor, means for connecting subscriber's lines through a connector switch to its circuit, a discriminating relay associated with each subscriber's line adapted for simplex signaling operative when a connector circuit is connected to a subscriber's line adapted for simplex signaling, an answering test relay in said connector circuit, means for signaling a 35 subscriber's line when connected to a connector circuit, means for connecting said answering test relay to a connected line during signaling, means for operating said answering test relay when the called subscriber answers, two 40 battery feed relays in said connector circuit adapted to feed ground or battery via the winding of one battery feed relay and battery via the winding of the other battery feed relay, means operative when the connector circuit is 45 connected to a subscriber's line adapted for simplex signaling and the associated answering test relay is operated and the associated discriminating relay is operated for feeding battery to said line via the winding of said battery feed 50 relays in simplex to both legs of the subscriber's line, and means operative when the connector circuit is connected to a subscriber's line adapted for loop signaling and the answering test relay is operated for feeding battery to one leg of 55 said line via the winding of one of such feed relays and ground to the other leg of said line via the winding of the other feed relay. 60
11. In a telephone system, common battery party lines, a line circuit for each line including a current feed relay, exchange equipment opera- 65
- tive in case of a revertive call for establishing a connection from the line circuit of a calling line at calling line terminals through the exchange equipment to the called line terminals of the same line circuit, a revertive call discriminating relay in said exchange equipment, means in said exchange equipment responsive when the calling subscriber replaces his receiver on the switch-hook in response to the calling line testing busy for ringing the called party and operating said discriminating relay, means in said exchange equipment operative when the called subscriber answers the call for operating said current feed relay in the line circuit of the calling line under control of said discriminating relay and for thereafter releasing said exchange equipment, and means for maintaining said current feed relay operated as long as either party's receiver remains off the switch-hook. 70
12. In a telephone system, single lines, common battery party lines, local battery simplex party lines, connector switches, a digit responsive control switch associated with each connector switch, means operative in response to the reception of a tens digit for setting a control switch to mark a corresponding group of lines, means responsive to the setting of said control switch for selecting said group of lines on the associated connector switch, means responsive to a unit digit for thereafter setting said connector switch on the terminals of the desired line, means responsive in case the desired line is a single line for testing said line, means operative in case the desired line is a party line for setting said control switch in response to a ringing code digit, and for transmitting the selected ringing code to the connected line to call the desired party, and discriminating means in said connector switch for determining whether the called line is a common 75 battery party line or a simplex local battery party line and for causing the ringing tone to be transmitted out over the connected line in a loop circuit in case the called line is a common battery party line or in a simplex circuit in case the called line is a local battery simplex party line. 80
13. In a telephone system, subscribers' lines adapted for simplex signaling, subscribers' lines adapted for loop signaling, connector equipment, means for connecting a calling line through said connector equipment to a called line and signaling said called line with the type of signaling required by said line, an answering test relay in said connector equipment, a current feed for said test relay, means for connecting said answering test relay to the called line intermittently between signaling periods so that the current feed is supplied to the called line in a simplex or in a loop connection as required by the type of line 85 connected. 90
14. In a telephone system, a first impulse responsive relay, a second impulse repeating relay, a third relay, an operating circuit for said second relay including operative contacts of said impulse responsive relay and normal contacts of said third relay, a locking circuit for said second relay including normal contacts of said third relay and operated contacts of said second relay, an operating circuit for said third relay including operated contacts of said second relay and a locking circuit for said impulse responsive relay including normal contacts of said second and third relay. 95
15. In a telephone system, a first impulse re- 100

sponsive relay, a second impulse repeating relay, a third relay, an operating circuit for said second relay including operative contacts of said impulse responsive relay and normal contacts of said third relay, a locking circuit for said second relay including normal contacts of said third relay and operated contacts of said second relay, a holding circuit for said second relay including operated

contacts of said first relay and operated contacts of said second relay, an operating circuit for said third relay including operating contacts of said second relay and a locking circuit for said impulse responsive relay including normal contacts of said second and third relays. 5
